UNITED STATES PATENT OFFICE.

CHARLES THOMAS COE, OF ALBANY, NEW YORK.

SECTIONAL SHAKING AND DUMPING GRATE.

1,121,001.

Specification of Letters Patent. Patented Dec. 15, 1914.

Application filed January 30, 1909. Serial No. 475,091.

To all whom it may concern:

Be it known that I, CHARLES THOMAS COE, a citizen of the United States, and a resident of Albany, in the county of Albany and State of New York, have invented certain new and useful Improvements in Sectional Shaking and Dumping Grates, of which the following is a specification.

This invention relates to a sectional shaking and dumping grate, which is characterized by dumping frames with grate sections, and means to secure the latter in said frames and prevent their detachment when using the grate.

Figure 1 represents a plan view of a grate with a portion of a furnace, exemplifying the invention, Fig. 2 is a partial front view and section of Fig. 1 on the line 2, 2, Fig. 3 shows a partial front view of Fig. 1, Fig. 4 is an enlarged fragmentary portion of Fig. 3, Fig. 5 shows an enlarged fragmentary portion of Fig. 1, Fig. 6 represents a plan view of a connecting bar and reach rod, Fig. 7 is an enlarged fragmentary front view of a dumping frame and a grate section, Fig. 8 represents a fragmentary modified portion of Fig. 7, Fig. 9 represents an enlarged end view of a dumping frame, Fig. 10 is a section of Fig. 7 on the line 10, 10, Figs. 11 and 12 show sections similar to Fig. 10 with modifications, Fig. 13 shows a front view of a grate section, Fig. 14 shows a side view of Fig. 13, Fig. 15 represents a top plan view of Fig. 14, Fig. 16 shows a front elevation of a filling block, Fig. 17 is a right hand side view of Fig. 16, and Fig. 18 represents a top plan view of Fig. 16.

The invention comprises a furnace having the supporting side bars 20 with the sockets 21 having cylindrical bearings 25 of greater diameter, than the distance between the vertical walls of the sockets, and the sockets 26 with cylindrical bearings 27 of a diameter equal to the distance between the walls of the sockets. In the ends of the said bars are formed dovetailed sockets 22, that engage lugs 23 of cross braces 24, which latter connect the ends of said frames.

Between the supporting bars 20 are located the dumping frames 30 comprising the end walls 31 and intermediate walls 32 and 33. The end walls 31 have each extending therefrom the segmental trunnions 34 with the flat faces 35, and the said trunnions are supported in the sockets of the

said frames 20. With each intermediate wall 32 is formed a leg 36 having the pin 37. The dumping frames have the connecting braces 40 with the lugs 41 and bearing braces 42, 43 extend between the end walls 31 and the intermediate walls 32, 33.

Grate sections 50 are located between the walls 31, 32, 33 and bear on the bearing braces 42, 43. Each grate section comprises the bars 51 that are formed with the connecting braces 52. The grate bars 51 are curved at their upper edges and at their front ends have formed therewith the heels 53 that bear on the braces 43, and at their front ends have the inclined bearing surfaces 54, that bear on the braces 42 which latter are beveled to gage with the said inclined bearing surfaces. From each grate section extends a lug 60 that is formed with a pair of the grate bars of said section. From each lug 60 extends a hook clamp 61 that engages with one of the lugs 41 of the connecting brace 40. It will be noted that the lug 60 extends below one of the connecting braces 52 so as not to obstruct the opening between them, although it may be located between them.

The pins 37 of the legs 36 of a number of the dumping frames 30 are joined by the connecting bar having the upper member 65 and the lower member 66. From the latter extends a lug 67 to which is secured a reach rod 68 by means of the jam nuts 69. From the front end of each reach rod 68 extends a forked connection 70. To the front 75 of the furnace are pinned the links 76 and a shaking link 77 connects each link 76 with the said forked connection.

Movable filling blocks with the upper 95 rectangular parallelepipeds 80 and the depending curved ribs 81 are located in the sockets. The shoulders 82 of the said blocks bear on the flat faces 35 of the segmental trunnions 34, the ribs 81 being located between the end faces of the trunnions of accompanying dumping frames 30. In a side frame that would be adjacent to a brick wall of a furnace one of the sides of the parallelepiped of the block would be adjacent to 100 said wall.

In Fig. 8 a fragmentary portion of a dumping frame is shown with a forked leg 83 and pin 84, in place of the leg 36 with the pin 37.

In Fig. 11 a dumping frame 90 is shown which has end walls, intermediate walls and

connecting braces similar to that shown in the dumping frame 30. It has a bearing brace 91 similar to 42, and its accompanying bearing brace 92 has formed therewith a shoulder 93 to support the heels 94 of the grate sections 95. The latter has extending from its grate bars a lug 96 which is in a plane about midway between the connecting braces 97 of the grate bars of the section. 10 A hook clamp 98 similar to 61 extends from the lug 96 and engages the lug 99 of the connecting brace.

In Fig. 12 a dumping frame is shown similar to that represented in Fig. 10, the 15 modification consisting in the hook clamp 100, which in this case is bent under the connecting brace 101 instead of engaging a lug of the latter.

To use the grate the operator preferably 20 by means of a shaking bar, reciprocates one of the shaking links 77 and thereby one of the sets of dumping frames 30 is moved thereby. When the frames 30 are swinging from their normal positions the flat faces 35 of the trunnions 34 raise the filling blocks in the sockets above the upper faces of the bars 20 disintegrating any portions of fuel thereon that may be coked, thereby preventing any fuel or ashes clogging up said 30 sockets and packing or caking around the trunnions so as to prevent their oscillations. The ribs 81 of the filling blocks maintain them in proper position when they are rising or lowering.

35 The segmental trunnions of the dumping frames are of a diameter so that they will nicely fit in the curved bearing surfaces of the sockets of the main side bars. To locate the trunnions on the bearing surfaces 25, the 40 dumping frames must be tilted when passing through the parallel sides of the sockets, so that the flat faces of the trunnions will be parallel to the said parallel sides of the sockets when the dumping frames are located in place. This disposition of the parts 45 locks the dumping frames with the main side frames and allows the former to swing, and prevents the dumping frames being lifted from the main frames when the grate is either dumped or shaken. This obviates

the usual unmechanical and complicated means of locking a dumping grate to a bar with wedges or blocks, and obtains an easy means to disengage the dumping frames from the side bars.

55

The end sockets as 26 must have a distance between their vertical walls equal to the diameter of the bearings, so that the end dumping frames can be lifted from and inserted in the main side bars without tilting. 60 Some of the other sockets are preferably of the same proportions so as to prevent the necessity of removing too many dumping frames when one of them is to be replaced.

The dumping frames can be combined as 65 desired. All may be operated at once, or various members may be connected with one reach rod.

Having described my invention, I claim:

1. In a grate the combination of supporting bars having sockets, each with a pair of parallel walls extending from the upper edge of each bar, the said walls connected by curved bearings of greater diameter than the distance between said walls, dumping 70 frames for the grate having segmental trunnions extending from the sides thereof, the said trunnions supported on said curved bearings and locked from displacement by said parallel walls, and means coacting with 75 said trunnions and sockets when moving the dumping frames to disintegrate any portions of fuel thereon.

2. In a grate the combination of supporting bars having sockets, each with a pair of parallel walls extending from the upper edge of each bar, the said sockets connected by curved bearings of greater diameter than the distance between said walls, dumping 80 frames located between the supporting bars 90 supported on said bearings, and movable filling blocks in said sockets vertically moved by the movements of the dumping frames.

Signed at the borough of Manhattan in the county of New York and State of New 95 York this 25th day of January A. D. 1909.

CHARLES THOMAS COE.
